UNITED STATES PATENT OFFICE.

RICHARD H. CUNNINGHAM, OF NEW YORK, N. Y.

DUAL IGNITION SYSTEM.

1,023,552.

Specification of Letters Patent. Patented Apr. 16, 1912.

Application filed January 29, 1910. Serial No. 540,781.

To all whom it may concern:

Be it known that I, RICHARD H. CUNNINGHAM, a citizen of the United States, residing at the city of New York, in the borough of Manhattan and State of New York, have invented certain new and useful Improvements in Dual Ignition Systems, of which the following is a full, clear, and exact description.

10 My invention relates to that variety of so called dual electrical ignition apparatus in which the low resistance primary circuit of an induction coil is energized by current derived at discretion from a suitable battery 15 or from a magneto alternating current dynamo.

My apparatus is adapted for use in means for producing electrical ignition in internal combustion engines, for the production of 20 high tension electric discharges, and provides means whereby in a dual system of ignition, the primary circuit of the induction coil when energized by the battery will be closed for a brief period of time just 25 previous to being subsequently interrupted by the same circuit breaker that is employed to interrupt the magneto current.

Another object of my invention is to provide a device whereby the intensity of battery current supplied to the battery circuit 30 of the coil may be limited to that simply necessary to energize the coil enough to produce a secondary spark of sufficient E. M. F., and intensity to fire the engine at 35 various speeds.

Another object of the invention is to produce a device and means whereby the occurrence of prolonged direct short-circuiting of the battery through the primary coil is 40 prevented; or at least markedly minimized when the engine is stopped with the selective switch closed on the battery circuit.

Another object of the invention is to increase the efficiency of the battery side of 45 the ignition and to permit an induction coil suitable for magneto actuation to be equally suitable for a battery current of a less mean voltage and thus avoid irregular fire or misfiring at high engine speed when running on 50 the battery.

I have further devised means whereby when starting the engine on the battery all danger of premature firing and consequent back kick of the explosive gas which is undergoing compression in the cylinder, is 55 eliminated.

Lastly, means have been provided, properly safe guarded from arcing, whereby a suitable momentary or series of momentary high tension sparks may be produced in the 60 proper cylinder of a resting multi-cylinder internal combustion engine containing an explosive mixture of gas under compression in one of the cylinders thereof.

Other novel features of my invention will 65 be more fully described hereinafter and pointed out in the claim.

One practical embodiment of my invention is shown in the accompanying drawings, in which like characters of reference 70 designate like parts throughout the several views.

Referring to said drawings: Figure 1 is a diagrammatic representation of a magneto circuit closing and interrupting device, 75 an induction coil and container therefor and connections between the several parts. Fig. 2 is an enlarged front view of my magneto circuit closing and opening device with the casing cover thereof removed. Fig. 3 is a 80 perspective front view of an induction coil container, the plan of connections between it and the magneto, and a front view of the magneto with the cover of the breaker box in position. Fig. 4 is a diagrammatic representation of the battery circuit. Fig. 5 is a 85 similar representation of the magneto circuit.

In Figs. 1 and 2 is shown a circular breaker box 1, which is adapted to be concentrically disposed about the axis of the magneto shaft. Pivoted to one side of the armature of this box is a spring pressed 90 lever 2, the pivoting pin being at 3. At the free end of this lever, a contact point 4, of 95 platinum or other suitable conductive material is affixed. A metal bracket 5, insulated from the containing metal box 1, is fastened to one side thereof by nuts 6, said nuts being electrically connected thereto but insulated from the box. The bracket bears an adjustable contact screw 7, provided with a platinum contact point 8, the latter being normally in contact with point 4 of the lever 2. 100

The armature shaft of the magneto carries upon the end thereof, an ovoid cam 9, the latter being keyed or otherwise secured to an extension 10 of said shaft. Extension 10 is the lead of the magneto winding, and is insulated from the shaft proper. 105

A metal bracket 11, preferably of brass,

is secured to the inner side of box 1, but is also insulated therefrom; and attached to bracket 11, but also in turn insulated from it, is a flat spring 12, bearing on its upper surface at the free end, a button 13 of fiber or other suitable insulating and resisting material. The bracket 11 is stepped as shown in Fig. 2, and to the middle step is secured the somewhat stiffer spring 14. Contact points 15 and 16 are respectively provided at the free ends of springs 12 and 14, these points being normally separated by about one sixty-fourth of an inch. A lead 12' electrically connects upper spring 12, with a terminal 17, the latter also being insulated from the metal box 1 and being provided with fixation nuts thereon. The lower spring 14 is in metallic connection with the bracket 11. Pivoted upon lever 2 is a roller 18 which bears against cam 9, and the position of this roller and button 13 of spring 12 are such that when the symmetrical ovoid cam rotates, for example, counter clockwise, one of the respective cam surfaces substantially in line with the long diagonal of the cam will act upon the button 13, forcing the two contacts 15 and 16 together, and then a few degrees later the corresponding opposite cam surface causes the elevation of lever 2, thereby separating contacts 4 and 8. As the cam continues to rotate, the shorter diameter will approach alignment with the button 13 and contacts 15 and 16 will again separate, so doing before contacts 4 and 8 actually again touch each other by reason of the formation of the cam. There is therefore but one short interval during a half revolution of the shaft when both sets of contact breakers are closed.

Referring now to Fig. 1, the container 19 of the induction coil has upon one face thereof the selective switch 20. On the bottom of said container are the terminals 21, 22, 23 and 24 which are connected by insulated wire respectively to terminals 25, 17, 10 and 6 of the magneto and circuit breaker. It should be here noted that terminal 25 is the remaining or grounded terminal of the magneto winding. On the upper surface of the container, terminals 26 and 27 indicate the two ends of the primary winding 28. Terminal 26 is connected to terminal 21 by lead 29 while terminal 27 is connected to the fixed contact 30 of switch 20. Binding posts 31 and 32 are connected to the respective terminals of battery 33. Post 31 is also connected to the fixed contact 34 of switch 20; while post 32 is connected to external terminal 22. Fixed contact 30 of the switch is electrically connected to fixed contact 35 and also to terminal 27.

The rotatable member of the switch comprises a hard rubber hub 36 which carries upon the under surface thereof the sector 37,

preferably of brass or bronze, and upon its outer surface the metallic sector 38, the sectors being hence insulated from each other. Sector 37 is in metallic contact with the hollow brass shaft 39 which is rigidly inclosed by the hub 36, the fixed contact 30 also being electrically connected to said shaft. Fixed contacts 40 and 41 are respectively connected to the terminals 23 and 24. Within the container are two condensers 42 and 43 of different capacities; one lead of each of which is connected to 26. The remaining lead of condenser 42, that of the larger capacity, is led via the terminal 45 to the elongated fixed contact 43' of the selective switch 20. The remaining lead of the condenser 43, that of the small capacity, is connected to binding post 32.

An open circuit push button 46 is inserted in a connecting lead extending between wire 29, which electrically connects terminals 21 and 26, and the lead connecting condenser 43 and binding post 32. When the switch 20 is turned to the position marked: "Bat." in Fig. 3, in which position it is also shown in Fig. 1, the cover being however removed, the course of the circuit at the moment that lever 2 is just about to be elevated by the cam is as follows: From the plus (+) pole of the battery to binding post 32, to terminal 22, to terminal 17 on the magneto breaker box, through insulated lead 12' to spring 12, spring 12 being at that instant in electrical connection with spring 14. Hence, from the latter through spring 14, bracket 11 and lead 47 to bracket 5, thence through screw 7, contacts 8-4, to lever 2, thence along the latter to magneto terminal 25 by way of the frame of the magneto, thence to terminal 21, wire 29, terminal 26 and through the primary winding to 27, and via the contact 30, segment 37 and contact 34 to binding post 31. The condenser 43 is thus across the point of break between contacts 4 and 8, which is the point at which it is best adapted to perform its function.

On the turning of the switch to utilize the magneto current, which position is indicated by the letters "Mag." in Fig. 3, the battery circuit is cut out; member 10 and the nut 6 become electrically connected by way of the switch, segment 37 of which engages contacts 40 and 41; and to terminal 27 by way of the connection leading thereto to shaft 39 and sector 37. Contact 35 is at all times connected with shaft 39, and contact 43' is correspondingly connected with terminal 45.

Considering the magneto circuit in detail: Current flows from the magneto armature winding to ground, thence for one branch of the divided circuit, from grounded terminal 25, through the connection leading to post 21; thence to terminal 26 and

through the primary coil to terminal 27, then through the connection leading therefrom to shaft 39 and segment 37. The other branch of the circuit includes the grounded 5 pin 3, lever 2, contacts 4-8, bracket 5, nut 6, connection therefrom to post 24, the respective branches reuniting at segment 37, which is in engagement with said contact. The entire current then passes through contact 40 from segment 37, through the lead therefrom to post 23 and thence to shaft 10 extension 10, and back to the armature.

Condenser 42 is electrically connected with terminal 45, and hence when sector 38 15 unites contacts 35 and 43', which latter is connected to terminal 45, the said condenser is thrown into the circuit parallel to the primary winding of the coil, as well as in shunt to the point of interruption of the 20 circuit at 4-8.

It is evident that with the switch turned to the battery operating position, if the engine is at rest, that since the pistons did not come to rest at the maximum point of 25 compression, the cam 9 will have its long axis more or less horizontal and will hence not cause electrical contact between springs 12 and 14; no current therefore can flow through the battery circuit and burn-outs 30 are hence avoided. In that position, however, if the pressure button 46 be pressed and quickly released, current passes momentarily from post 32 across the button to terminal 26, through the primary winding 35 to 27, and thence by way of the switch connections to post 31 of the battery. A high tension current is induced in the secondary, which will, if conducted as usual to a distributor as indicated in Fig. 3, with 40 a suitably proportioned distributing segment, pass to that cylinder of the engine whose piston has last passed completely over the point of maximum compression, and provided that the relatively adjustable 45 spark advancing and retarding mechanism have been properly designed and adjusted, will effect the production of the ignition spark in the said cylinder. Owing to the fact that condenser 43 is of suitable capacity and is in shunt with the contacts of the 50 press button 46, the said contacts are subjected to practically no arcing.

I have shown in Figs. 4 and 5 diagrammatic representations of the respective battery and magneto circuits which show at a 55 glance the relative positions of the several elements in such circuit.

I particularly wish to point out the value of my automatic circuit breaking device by 60 the action of which I obtain ignition at the proper instant in the engine cycle whether

the battery or the magneto be in use; the device operating when on the battery circuit to conserve the battery by keeping the circuit closed the shortest possible time, and 65 operating equally well when the magneto is in use; in such case serving to maintain the magneto in short circuited condition during the greater portion of the time. Hence in one case my breaker box permits a flow of 70 current therethrough for an instant only, while in the other the current flow is maintained for an extended interval of time. In so far as I am aware there has never been any successful attempt heretofore to so operate a dual system of the kind in question and the results achieved are of value.

In starting an engine by the previously described so called method of "swinging", the cam 9 will oscillate back and forth, possibly far enough in the reverse direction for the lever 2 to be elevated, but since the contacts 15 and 16 are not in contact when said cam is in that position, even if the switch is turned to battery position, no spark occurs 85 unless the reversed motion of the cam continues until the cam has so far rotated that contacts 15 and 16 may separate. As such a condition can be brought about only by the engine swinging backward completely over 90 the center, a procedure that never occurs, it is evident that premature explosion of gas in the cylinders due to mis-timed or irregularly produced sparks is eliminated, by the 95 above described mechanism.

Having described my invention, what I claim, is:

In a dual system of electrical ignition, a circuit making and breaking device comprising a plurality of circuit breakers, and 100 means for successively operating said circuit breakers, a switch, a battery, a magneto and an induction coil primary winding, the above recited elements being electrically connected up and so coöperating with said 105 circuit making and breaking device that when the switch is in battery circuiting position, current will flow through said winding for but a small fraction of a recurrent time interval, and with the switch in magneto circuiting position, said device will permit of maximum current flow through the magneto armature during the major portion 110 of said time interval, two of said circuit breakers being in series when the switch is 115 in said battery circuiting position.

In witness whereof, I subscribe my signature, in the presence of two witnesses.

RICHARD H. CUNNINGHAM.
